VACUUM FLOOR CLEANER

Filed Oct. 21, 1936

UNITED STATES PATENT OFFICE

2,078,101

VACUUM FLOOR CLEANER

Lydia M. Schmermund, St. Louis, Mo.

Application October 21, 1936, Serial No. 106,823

3 Claims. (Cl. 15—10)

My invention relates to improvements in vacuum floor cleaners and polishers and the main object is to provide a machine by which all dust and other particles may be brushed up from the floor and drawn by suction up into a bag and which includes also a polishing pad for simultaneously polishing the floor.

Another object is to provide a machine of this kind in simple and conveniently usable form comprising a rectangular housing atop which is mounted a motor, suction fan, dust bag and handle assembly of substantially conventional form but the said housing having dual suction inlets arranged at opposite or front and rear ends, and there being brushes located adjacent and inwardly of each inlet so that dust particles and the like brushed up by these brushes when the machine is moved either way or back and forth over the floor will be drawn up through these inlets to the bag.

A further object is to provide a machine of this kind including also a polishing pad of felt or other resilient material located between the aforesaid brushes and adapted to polish the floor after it has been brushed clean by the brushes.

Another object is to provide a device of this kind in which the said housing is provided at its sides with concaved depressions lined with felt or other suitable material for cleaning around the legs of tables or other heavy articles of furniture.

With these and other objects in view the invention resides in the novel construction and arrangement of parts as hereinafter fully set forth and claimed, reference being had to the accompanying drawing as showing a preferred embodiment of my invention for purposes of exemplification.

In the drawing:

40 Figure 1 is a perspective view of a cleaning and polishing machine constructed in accordance with my invention and showing the same in use on a floor and cleaning around a table leg.

45 Figure 2 is an enlarged side view partially in vertical longitudinal section of the housing and motor portion of the machine.

Figure 3 is an inverted plan or bottom view of the machine, a portion of one brush and of the pad being broken away.

50 Figure 4 is a further enlarged fragmental vertical cross section through one end of the machine.

55 In carrying out my invention I provide a housing shown generally at 5 of substantially rectangular form in plan and which includes an out-

er wall portion 6 and smaller inner wall portion 7. At the sides the portions 6 and 7 are joined and held in spaced relation thus providing an air chamber 8 beneath the entire top of the said outer portion. The front and rear ends of the portions 5 6 and 7 are then turned down in spaced relation as at 9 forming narrow front and rear suction inlets 10 and 11 extending the entire width of the housing. A fan housing 12 is formed integrally with the housing portion 6 at its center and communicates with the air chamber 8 as at 13. An electric motor A is mounted atop this housing 12 and drives a suction fan B therein and a suction outlet C leads from the housing for connection to a conventional dust bag D. A handle E has 10 a hook F to support this bag D and the fork G of the handle is pivoted at 14 to ears 15 which are extended upwardly from the housing 12 each side of the motor. The upper ends of the ears 15 have bosses 16 punched or formed inwardly 15 and the fork G at each side has shallow sockets 17 into which these bosses 16 will enter when the handle E is turned upward to a vertical position thus releasably holding the handle thusly while the machine is not in use and facilitating storage. 20 When the motor A is in operation it turns the fan B and sets up a suction up through the aforesaid inlets 10 and 11 as will be readily apparent.

Another object is to provide a device of this kind in which the said housing is provided at its sides with concaved depressions lined with felt or other suitable material for cleaning around the legs of tables or other heavy articles of furniture.

A flat rectangular mounting plate 18 of such size as to fit up into the housing beneath the lower section 7 thereof is provided and is removably secured in this position by screws 19 screwed up into the housing. Adjacent each end of this mounting plate 18 a pair of spaced parallel brush mounting springs or spring strips 20 is provided. 30 These strips are of elongated form to extend entirely across the plate 18 and have base mounting angles or feet 21 by which they are riveted as at 22 to the plate. The extremities of each pair of the strips are curved or turned inwardly toward each other forming shoulders or hooks 23. Conventional elongated bristle brushes 24 are mounted to the plate by sliding their backs 25 into the channels formed between the strips 20 wherein the brushes then are held with the 35 bristles turned downwardly by engagement of the hooks 23 with the edges of the backs 25. When the mounting plate 18 is removed the brushes 24 may of course be readily slipped out endwise and removed for cleaning or replacement.

A mounting block 26 of wood or any other suitable material is secured by screws 27 to the plate 18 and is of rectangular shape to fit nicely up into the housing 5 between the brushes 24. Around its margins the block 26 has the female 50

members 28 of conventional snap fasteners secured in spaced relation. A polishing pad 29 of felt, sheep's wool or other suitable material is provided and is of such shape and size that when placed against the lower flat face 30 of the block 26 the margins 31 of the pad will extend all around and may be turned up over the margins of the block. These margins 31 then have the male members 32 of the snap fasteners secured 5 to them and by engaging the snap fastener members the pad may be stretched tightly over the block and will present a flat even lower surface reinforced and backed up by the block as will be understood.

10 In use the machine is supported on the floor by the flat face of the pad 29 with the brushes 24 in contact with the floor but with the lower margins of the housing 5 clear of the floor. The motor then being set in operation the machine is moved back and forth over the floor and on the forward movement the frontal or leading brush 24 will brush up all dust particles and the like on the floor and brushing these particles ahead will allow the suction in the frontal inlet 20 10 to draw them up and finally deposit them in the bag D. The following pad 29 will thus operate upon a clean floor and will polish it without injury due to scratches or the like from particles beneath the pad. As the machine is pulled back the rear brush 24 becomes the leading one and throws any particles left up into the rear inlet 11. Thus the brushes clean ahead of the pad in both directions in which the machine is moved and this greatly facilitates cleaning especially up near walls or other obstructions. The ends 9 of the inner or lower housing section 7 are turned inwardly at their extremities at 9a so that the inlets 10 and 11 fall at their inner margins immediately adjacent 30 35 the brushes 24 to facilitate the picking up of dirt brushed up by these brushes as will be understood.

The opposite lateral margins of the housing 5 have medial concaved depressions or recesses 33 45 which are lined as at 34 with felt or other resilient material and thus by engaging these lin-

ings with the legs L of a table T or other article of furniture as shown in Figure 1 the legs may be dusted at the floor line. The mounting block 26 and pad 29 are of course cut out as shown at 35 to fit where these recesses 33 are 5 formed.

A rubber bumper strip 36 secured around the margins of the housing 5 prevent injury to furniture by the machine striking it in use.

While I have herein set forth a certain preferred embodiment of my invention, it is understood that I may vary from the same in minor structural details so as best to provide a practical device for the purposes intended, not departing from the spirit of the invention and 10 within the scope of the appended claims.

I claim:

1. In a device of the kind described, a housing having an air chamber and parallel inlet slots at opposite ends, a suction fan and motor mounted 20 on the housing, brushes mounted on the housing parallel to and inward of the said inlet slots, and a polishing pad mounted on the housing between the said brushes.

2. In a device of the kind described, a rectangular housing having an air chamber and parallel downwardly opening air inlet slots at opposite ends, a suction fan and motor mounted on the housing, brushes mounted beneath the housing parallel to and inward of the said air 30 inlet slots, and a rectangular polishing pad mounted beneath the housing and between the said brushes.

3. In a device of the kind described, a rectangular housing including inner and outer portions spaced apart to form an air chamber, a suction fan and motor mounted on the housing, the ends of the housing portions being turned downwardly to form narrow parallel air inlet slots at each end of the housing, a mounting 40 plate secured beneath the housing between the said air inlet slots, a brush removably mounted at each end of the mounting plate parallel to the air inlet slots, and a polishing pad mounted on the mounting plate between the said brushes. 45

LYDIA M. SCHMERMUND.
